UNITED STATES PATENT OFFICE.

ROBERT R. PARRY, OF ELMHURST, NEW YORK, ASSIGNOR OF ONE-HALF TO CARL H. FOWLER, OF NEW YORK, N. Y.

APPARATUS FOR DRYING AND POLISHING DRINKING GLASSES.

Application filed January 2, 1925, Serial No. 68. Renewed March 14, 1928.

The invention relates to apparatus for drying and polishing drinking glasses, or the like articles. It relates more particularly to apparatus whereby a tumbler or drinking glass, or article of similar shape, may be effectively and quickly dried and polished, by an automatic mechanism, after the article has been washed.

In accordance with the invention devices are provided for rotating a glass or tumbler or similar article inserted in the apparatus, the rotating article being thoroughly dried and polished by engagement with suitable surfaces. The rotating article preferably engages drying and polishing material which is either stationary or is provided with a slow feeding movement, in order to remove wet portions of the same and replace them by dry portions. Preferably the drying members will engage against the outer and inner cylindrical surfaces of the article, the inside of the bottom, and if desired, the outside of the bottom. The device preferably is adapted to operate upon articles of somewhat varying size and shape, such as different forms of drinking glass. Preferably also the machine is automatically set in operation by the act of placing the glass therein, so that the glass will be rotated for a suitable time interval, at the end of which time the moving parts are preferably automatically stopped.

An object of the invention is the provision of efficient and comparatively simple devices of the character referred to. Other objects of the invention comprise the provision of various combinations of parts and forms of construction, all as will be more fully described in the following specification and be particularly pointed out in the appended claims.

In order that the invention may be more clearly understood attention is hereby directed to the accompanying drawings, forming part of this application and illustrating one form of apparatus embodying the invention. In the drawings

Fig. 1 represents a side elevation of apparatus embodying the invention;

Fig. 2 is a top plan view of the same;

Fig. 3 is a vertical section taken on line 3-3 of Fig. 1;

Fig. 4 is a horizontal section taken on line 4-4 of Fig. 1;

Fig. 5 is an enlarged vertical section 55 through the tumbler support with tumbler mounted thereon, and through adjacent parts, this figure being similar to the upper portion of Fig. 3, but with the tumbler in position;

Fig. 6 is a horizontal section taken on line 6-6 of Fig. 5, and

Fig. 7 is a partial vertical section similar to the lower portion of Fig. 5, but showing the portion upon a tumbler of flaring shape.

Referring to the drawings, the apparatus as shown comprises upper and lower horizontal plates or supports 1 and 2 mounted upon and supported by suitable legs or vertical supports 3.

A stationary tumbler or article support 4 extends upwardly above top plate 1. This support is preferably cylindrical and may be formed of pressed metal or the like, if desired, with a top closure 5. This cylindrical support is shown as mounted upon and extending upwardly from a plate 6 secured upon the fixed plate 1 of the apparatus.

A tumbler 7 may be positioned upside down upon support 4. When so mounted 80 the tumbler will engage a pair of rotatable cylinders 8, 8. These cylinders 8 are mounted upon or carried by vertical spindles 8¹, 8¹, which extend downwardly through top plate 1 in which they have journal bearings, 85 lower ends of these spindles being provided with suitable bearings on the bottom plate 2.

The tumbler when inverted over support 4 will be pressed into contact with cylinders 8 by engagement of cylindrical support 4 90 with the inner surface of the tumbler at a point intermediate the cylinders 8. The tumbler will be rotated during the drying operation by the rotation of cylinders 8, which may be accomplished in various ways. 95 Cylinders 8, may, if desired, be provided with suitable friction surfaces.

Preferably the machine is set in operation automatically upon the insertion of the tumbler therein and the tumbler rotated for a 100 predetermined short interval. In the construction shown in the drawings a motor 9 is provided mounted upon bottom plate 2, this motor being connected to horizontal shaft 10 carrying worms 11, 11, which mesh with 105 worm wheels 12, 12, on spindles 8¹.

The motor may, of course, be switched on and off when the tumbler is placed in the

apparatus, and when its drying is completed, by various forms of devices. In the form of construction illustrated a vertical rod 13 extends upwardly through tumbler 4 and a short distance above top closure 5 of the support, above which rod 13 is provided with a horizontal plate 14, which may be of the shape indicated in Fig. 6 for a purpose subsequently to be explained. Rod 13 extends downwardly through the plates 6 and 1 and at its lower end it has a pivotal connection with arm 15 which is pivoted intermediate its ends at 16 to a pedestal 17 extending upwardly from plate 2.

The opposite end of arm 15 is pivotally connected to a vertical plunger 18 which is movable into and out of a switch device 19. When the weight of the tumbler is placed on plate 14 above the top of support 4 rod 13 will, of course, be depressed and plunger 18 will be moved upwardly into the switch box 19. This upward movement of plunger 18 will close contacts within box 19, which will close the motor circuit, and immediately cause the rotation of cylinders 8 and the consequent rotation of the tumbler which is engaged thereby.

Various forms of make and break devices 30 may be used for the switch, and it is not deemed essential to illustrate the construction of the contacts within box 19. This may be for example a switch device of the type known as a canopy switch. It is preferably provided with a form of impulsive lock so that plunger 18 will remain in its upper or lower positions until it is moved therefrom.

As stated, the preferred form of the invention also includes means for automatically stopping the rotation of the cylinders 8 and consequently of the tumbler 7 after the latter has been rotated for a desirable short time. This may suitably be accomplished by mechanism for automatically stopping the motor after a predetermined number of operations as illustrated. One of the spindles 8¹ is provided with a worm 20 which meshes with a worm wheel 21 on a horizontal shaft 22 which extends transversely across the machine and is supported by suitable brackets or pedestals 22¹ which extend upwardly from bottom plate 2.

Shaft 22 is also provided with a cam 23. A bell crank lever having upper and lower arms 24^a, 24^b, is pivotally mounted at 25, to support 22¹, and carries, at its upper end, a roller 26 which bears against the outer surface of cam 23. An arm 27 is pivotally mounted at one end at 25, the other end of this arm being pivotally connected at 28 to the plunger 18 of switch device 19. Arm 27 and the lower arm 24^b of the bell crank are provided with faces which are adapted 85 to engage as indicated at 29 Fig. 1. A

spring 30 connecting arm 27 with the lower arm 24^b of the bell crank tends to hold these faces in engagement.

Cam 23 is provided with a nose 31 against which roller 26 bears when the device is not in operation. When a tumbler is positioned on support 4, which starts the motor in operation by the downward movement of rod 13, the swinging of arm 15 and the upward movement of plunger 18, as has been explained, the arm 27 moves upwardly with plunger 18 against the pressure of spring 30. Cam 23 immediately starts rotating in a counter-clockwise direction, referring to Fig. 1, and roller 26 drops off of nose 31 of the cam whereupon the lower arm 24^b of the bell crank moves upwardly a distance permitted by the engagement of roller 26 with the peripheral cylindrical surface of cam 23, and by the engagement of the coacting faces at 29. The contacts of switch 19 accordingly remain closed during one complete rotation of cam 23 during which the tumbler which is to be dried and polished is rotated as has been explained. At the end of one rotation of the cam, roller 26 will again ride out on the nose 31 of the cam, depressing the lower arm 24^b of the bell crank whereupon spring 30 pulls down arm 27 and plunger 18 to break the contacts within switch device 19 and accordingly stop the motor.

The devices by which the tumbler will be dried and polished during its rotation will now be described. This is preferably accomplished by the provision of a pair of strips of suitable material against which the inner and outer surface of the tumbler will rub during the rotation of the latter. These strips are preferably tapes of suitable textile material which are passed around suitable guiding and holding means and are given suitable feeding movements, as is required, in order to present dry surfaces to the portions of the tumbler against which they bear.

One of these strips or tapes 32 is wound around a vertical spool 33, Fig. 2, this spool being mounted on a suitable vertical spindle extending upwardly from plate 1. The tape passing off from spool 33 passes around a vertical roller 34 which extends upwardly from the plate 6, which is secured on the fixed plate 1 of the machine. This member 34 may take the form of a sleeve mounted upon a bolt 35, Fig. 5. Bolt 35 passes through an opening in a small horizontal plate 36, which is provided at a height slightly above the upper surface of the tumbler 7 when the latter is positioned on support 4. This plate 36 may be supported from plate 6 by vertical screws 37 or the like, Fig. 2, which may be provided with suitable shoulders or with spacing sleeves about the screws for supporting plate 36. A

bolt 38 is also provided similar to the bolt 35 and provided with a sleeve about the same identical with sleeve 34 mounted on bolt 35.

Tape or strip 32 passes about roller or sleeve 34, as stated, and then extends forwardly, or towards tumbler 7, for a distance, until it passes around a vertical pin 39, which extends downwardly from plate 36, see Figs. 2 and 5. The strip then extends to the left, referring to Fig. 2, for a distance and passes about a second pin 39, identical with the one just referred to. The strip then extends rearwardly, about the roller on bolt 38 and then extends off at an angle to the left, Fig. 2, and is wound upon a take-up reel 40 which extends upwardly from plate 1, parallel to the reel 33.

It will be noted that tape 32 is of a width which may be approximately equal to the height of the tumbler 7, that is, this tape may be sufficiently wide to rub against the outer cylindrical surface of the longest tumbler which will be dried. The exterior surface of the tumbler will bear against this tape at a point intermediate the two pins 39, (see Fig. 6). Good contact between the glass and this tape 32, is insured by a leaf spring 41 which is preferably secured within tumbler support 4. The tumbler support is provided with a vertical slit through which spring 41 extends, the spring serving to press the adjacent wall of the tumbler against the adjacent portion of strip 32, as is shown in Figs. 3 and 5. This spring also serves to press the inner tape against the inside surface of the glass, as will be later explained. This spring may be secured, for example, upon a disc 42 mounted within the bottom end of the tumbler support 4.

Strip 32 may be fed forwardly upon take-up reel 40 in any suitable way, so as to provide a dry portion of the strip 32 between pins 39, as is needful. As is indicated in the drawings, this may be accomplished by the provision of a pinion 43 on one of the rotating vertical spindles 8¹. This pinion meshes with a gear 44 mounted on a short stud extending upwardly from plate 1. A pawl 45 is mounted eccentrically on gear 44 and the nose of this pawl engages the teeth of a ratchet 46 on the spindle of take-up reel 40. Strip 32 will accordingly be advanced continuously at a slow rate, and wound up on reel 40, throughout the rotation of the tumbler. A pawl 47 may be provided to prevent backward motion of reel 40 and a spring 48 is indicated as connecting the tail of pawl 47 with the pawl 45, so as to maintain both pawls in engagement with ratchet 46.

The inside surfaces of the tumbler are dried by a strip of material 49, similar to the strip 32. Strip 49 winds off of a reel 50 which is shown, Fig. 1, as mounted beneath plate 2. The strip passes around a roller 51,

which extends downwardly from plate 2 at an angle of 45 degrees, so that the tape will be directed vertically upward therefrom, as is indicated at 49^a, Figs. 1 and 3.

The tape passes around a roller 52 at the edge of upper plate 1 and proceeds rearwardly for a short distance over plate 1, as is indicated at 49^b. It then passes around a roller 53 and extends upwardly therefrom, as is indicated at 49^c, until it passes over the adjacent edge of the cap piece 14 mounted on the upper end of rod 13 within the tumbler support 4. The tape passes across the top of cap piece 14, as is indicated at 49^d, and then extends downwardly over the opposite edge of cap piece 14. The cap piece 14 may be provided with guiding fingers 14¹ for guiding the tape across the same.

The downwardly extending portion 49^e of the tape passes around a roller 54, mounted above plate 6. It then extends horizontally above plate 1, as is indicated at 49^f, over a roller 55 at the edge of plate 1, thence downwardly, as is indicated Fig. 3 at 49^g, thence around a forty-five degree roller 56, from which the tape passes onto a take-up reel 57, mounted on a vertical spindle below plate 2.

The tape portion 49^h passing above cap 14 will rub against the inner surface of the bottom of the tumbler 7 when the latter is positioned thereon, as shown in Fig. 5, so that this surface, 7^a, will be dried and polished by the contact with the strip. The downwardly extending portion 49ⁱ of the strip will bear against the inner cylindrical surface of the tumbler when the latter is positioned therein, as shown, Fig. 5, so that this surface will be effectively dried and polished thereby. The spring 41, previously referred to, serves to press the portion 49^j of the drying strip against the inside vertical surface of the glass. When no glass is in position to be operated upon, the portion 49^k of the strip 49 will extend somewhat at an angle from the upper edge of cap piece 14 to the roller 54, as is indicated in Fig. 3, in which position it will bear somewhat against the adjacent portion of the outer drying strip 32 extending between pins 39, 39. When the tumbler is inserted in position for drying, it will press apart the drying strips 32 and 49, and will take a position between them, engaged on the inner and outer sides by strips 49 and 32, as is indicated in Fig. 5.

Tape or strip 49 is fed onto the take-up reel 57 during the rotation of the tumbler by suitable means, such as a pawl 58 which coacts with a ratchet 59 on the shaft of take-up reel 57. The construction of the feeding devices for this strip may, as illustrated, be the same as those for the other strip 32. That is, as shown, pawl 58 may be mounted eccentrically upon a gear 59 which meshes with a pinion 60 on the spindle of the right-hand rotating cylinder 8, 130

Fig. 2. A pawl 61 is also indicated for preventing return motion of ratchet 59 and a spring 62 is indicated as connecting the tail of pawl 61 with the pawl 58 so as to keep both pawls in engagement with the ratchet.

Means for drying and polishing the outer bottom surface of the tumbler may be provided, if desired. This may take the form of a drying member 63, pivotally mounted 10 at 64 to a bracket on plate 36. This member may be swung back out of the way, as shown in Fig. 3, until a tumbler is in position to be dried, whereupon member 63 may be swung downwardly into the engaging position shown in Fig. 5.

It will be noted that the vertical pins 39 about which tape 32 extends preferably extend downwardly for a distance considerably less than the height of the tumbler.

20 With this arrangement strip 32 will engage against the entire length of a cylindrical or tapered tumbler positioned in place, as shown in Fig. 5, pins 39 being of a length sufficient to provide enough bearing for strip 32 for this purpose. If, however, a tumbler 71 having an outwardly curved lower end be inserted in the apparatus, as is indicated in Fig. 7, in this case the outer strip 32 and the inner strip 49 will both be 25 able to lie against the curved lower surface of the inverted tumbler. In this case the pins 39 will hold the outer strip 32 in firm contact with the straight portion of the tumbler, while the curved portion of the tumbler below pins 39 will cause the downwardly extending portion of strip 49, before the latter passes over roller 54, to follow and press against the inner curved surface of the tumbler. The outer strip 32 will be pressed 30 backwardly a sufficient amount by the belled portion of the tumbler below pins 39 but will continue to bear against this portion of the tumbler.

It is believed that it will be clear from the 45 above that the various surfaces of the tumbler will be effectively dried and polished and provided with a high polish, by the action of the various drying surfaces described, during the interval of time through 50 which the tumbler is rotated.

It should be understood that the invention is not limited strictly to the details of construction which have been particularly described, but that the invention is of a considerable breadth, as is indicated by the accompanying claims.

What I claim is:

1. In drinking glass drying apparatus, the combination of a stationary vertical support 60 of less diameter than a glass which may be loosely positioned, inverted, thereon, rotatable means for pressing one side of a glass thus positioned, towards said support, and for rotating the glass thereabout, and

drying means positioned to be rubbed 65 against by the rotating glass.

2. In drinking glass drying apparatus, the combination of a vertical support of less diameter than a glass which may be loosely positioned, inverted, thereon, rotatable 70 means for pressing one side of a glass thus positioned, towards said support, and for rotating the glass thereabout, and horizontally mounted drying means at the top of said support, on which the under surface of 75 the bottom of the inverted glass will be supported as it rotates over the same.

3. In drinking glass drying apparatus, the combination of a vertical support of less diameter than a glass which may be loosely 80 positioned, inverted, thereon, rotatable means for pressing one side of a glass thus positioned, towards said support, and for rotating the glass thereabout, and drying means extending between said support and 85 the glass, adjacent to said rotatable means, adapted to be rubbed against by the rotating glass.

4. In drinking glass drying apparatus, the combination of a support, drying means 90 adapted to bear against surfaces of a glass thereon, and means for automatically rotating the glass for a desired period, in contact with said drying means, operated by the placing of the glass upon said support. 95

5. In drinking glass drying apparatus, the combination of a support, drying means adapted to bear against surfaces of a glass thereon, means for rotating a glass about 100 said support, in contact with said drying means, and means for starting said rotating means automatically, operated by the placing of the glass on said support.

6. In drinking glass drying apparatus, the combination of a vertical support of less diameter than a glass which may be loosely positioned, inverted, thereon, rotatable 105 means for pressing one side of a glass thus positioned, towards said support, and for rotating the glass thereabout, and drying 110 means extending over the top of said support and along the vertical surface thereof, adjacent to said rotatable means, adapted to bear against the underside of the bottom 115 of the inverted glass and the longitudinal surface of the glass, when the latter is rotated.

7. In drinking glass drying apparatus, the combination of a vertical support of less diameter than a glass which may be loosely positioned, inverted, thereon, rotatable 120 means for pressing one side of a glass thus positioned, towards said support, and for rotating the glass thereabout, and drying means extending over the top of said support and along the vertical surface thereof, adjacent to said rotatable means, adapted to bear against the under side of the bottom 125

of the inverted glass and the longitudinal surface of the glass, when the latter is rotated, said drying means comprising a continuous strip, and means for feeding said strip lengthwise to present dry portions thereof to the glass.

8. In drinking glass drying apparatus, the combination of a support for a glass, means for rotating the glass, an elongated strip of fibrous material for drying the glass, and means for positioning the same with a length thereof in contact with a surface of the rotating glass.

9. In drinking glass drying apparatus, the combination of a support for a glass, means for rotating the glass, members adapted to dry the inner and outer surfaces of the glass, means for giving said members a slight feeding movement only during the drying operation, to advance dry surfaces thereof into contact with the glass, and means for holding the same in contact with inner and outer surfaces of the rotating glass.

25 10. In drinking glass drying apparatus, the combination of a support for a glass, means for rotating the glass, a strip of fibrous material for drying the glass, means for causing the same to press against a surface of the rotating glass, and means for

feeding said strip lengthwise to present dry portions thereof to the glass.

11. In drinking glass drying apparatus, the combination of a vertical support of less diameter than a glass which may be loosely positioned, inverted, thereon, a pair of rotatable cylinders mounted to press one side of a glass thus positioned, towards said support, and for rotating the glass thereabout, a drying strip, and bearing means for the same adapted to press a length of said strip against the outer surface of the glass between said pair of cylinders.

12. In drinking glass drying apparatus, the combination of a vertical support for an inverted glass, rotatable means for pressing one side of a glass positioned thereon towards said support and for rotating the glass thereabout, a drying strip, and vertical pins about which the same extends, including a pair of pins extending downwardly adjacent to the outer surface of the glass, for a portion only of the length of the glass, the length of strip extending between said pair of pins being adapted to press against the exterior surface of the glass.

In testimony whereof I have signed my name to this specification.

ROBERT R. PARRY.
